UNITED STATES PATENT OFFICE.

FREDERICK HENRY DAY, OF DAWSON, YUKON TERRITORY, CANADA.

BINDING-POST.

1,132,454.

Specification of Letters Patent. Patented Mar. 16, 1915.

Application filed September 3, 1913. Serial No. 787,869.

To all whom it may concern:

Be it known that I, FREDERICK HENRY DAY, a citizen of the Dominion of Canada, residing at Dawson, Yukon Territory, Canada, have invented certain new and useful Improvements in Binding-Posts, of which the following is a specification.

The present invention appertains to improvements in binding posts, the object in view being to provide a device of this character capable of receiving and automatically seating one or more wires, cables, ropes, or the like, in positive engagement with the post. To the end accomplishing this purpose, I employ a post on which are movably mounted clamping members normally placed under pressure, these members coöoperating in such a manner that one or more wires may be quickly inserted therebetween, the shape of the members facilitating such entering action as well as insuring positive contact of the wire with the stem of the post when designed particularly for use as an electrical terminal. Furthermore, it is contemplated in my invention to provide the clamping members with novel retaining means for preventing accidental disengagement of the wire, or like member, from the post when strain is exerted on such wire, deliberate separation or relief of the pressure on the clamping members being required to accomplish this result.

For a full understanding of the present invention, reference is to be had to the following description and to the accompanying drawings, in which—

Figure 1 is an elevation of a device embodying my invention. Fig. 2 is a longitudinal sectional view of the same. Fig. 3 is a sectional view of one of the clamping members alone. Fig. 4 is a fragmentary sectional view showing a wire clamped in position. Fig. 5 is a sectional view of the base of the binding post alone. Fig. 6 is a view showing a modified arrangement of the parts comprising my device.

Referring to the drawings and specifically describing my invention, 1 represents the main support or structure to which the binding post is attached as by means of a screw or like fastening member 2 secured in the base 3 of a suitable size and configuration.

At the top of the base 3 is located the stem or post 4, the lower threaded end 4' of which is screwed into an internal threaded recess 5 in said base. Movably mounted in

superposed relation upon and encircling the stem 4 are provided one or more clamping members, the number of which is governed by the use for which the device is designed, but, as illustrated in the drawings, comprising three such members, 6, 7 and 8, respectively. Each of the ring-like clamping members is formed with an annular flange 9, and beveled inwardly above said flange directly adjacent to an internal recess 10, which is somewhat cup-shaped and forms the terminal of the stem opening 10' through the clamping member. Each of said members excepting the lowermost one is beveled or reduced beneath the flange also, the reduced portion extending into the recess 10 of the next lower member. The lowermost clamping member, on the contrary, beneath the flange 9, is formed with an integral, elongated ring or annulus 11, which is adapted to act as a gland, and to be received into a corresponding recess 12 in the base 3 upon an expansion spring 13. The top of the stem 4, similar to its bottom extremity, is threaded, and secured upon the stem is a removable cap or head 14 which retains the clamping members on the stem against the common tension member or spring 13, the latter being capable of exerting considerable pressure for obvious reasons, more readily understood as this description proceeds.

In the use of the invention, the wire, rope, or other flexible member 15, as the case may be, is brought around the post between a pair of these clamping members, stress being applied to the wire which, by reason of the beveled or tapering surfaces of the members will slip into a recess 10 beneath the reduced portion of the superimposed clamping member, where it will be readily held. As will be apparent to those skilled in this art, the shape of the recess 10 is such that the reduced portion of the same, where it approaches the opening 10' insures that the wire will be pressed into intimate contact with the stem 4, this being essential where the binding post forms an electrical terminal. The foregoing illustrates the facility with which the member 15 may be connected to or engaged with the binding post but it will be understood that where this facility is not an essential requirement, or when the occasion so requires, the wire may be very easily inserted by depressing a lower member against the pressure of the

spring 13, the diameter of which lower clamping member, or more correctly speaking, its flanged portion, being increased over that of its superposed member to permit of 5 readily separating the same with the fingers.

In order to insure a positive clamping of the wire in place, the annular edge portion of the clamping members around the recess 10 is notched, as indicated at 16, most 10 clearly seen in Fig. 3 of the drawings, and the wire will interlock with these notches, thereby eliminating likelihood of the same being unwound from the post under action of any pull or stress thereon.

15 In Fig. 6 I have shown a slightly modified arrangement of the parts constituting the binding post, wherein the cap or head 14^a is recessed, as shown at 12^a to receive the spring 13, while the clamping member 6 20 having the elongated annulus or gland 11^a seated against the spring, is inverted to permit the annulus to move into this recess. The upper portion of the base 3^a is rounded so as to facilitate, in coöperation with the 25 contiguous reduced portion of the clamping portion 6, the reception of the wire into clamping position therebetween.

I have only illustrated in this modified form a single ring member 6 and it will be 30 equally clear that I may, in the preferred form, use any convenient number of these members, it being necessary only to substitute a different length stem when adding more, or reducing the number of the same.

35 It will be evident that the binding post constituting my invention is especially adapted for use wherever there is more or less vibration such as in conjunction with automobiles, airships, motor boats and the like. 40 When once the wire has been engaged and contact made, it is quite impossible to be broken unless force is applied at the proper point, there being no parts which would work or jar loose.

45 In the broader phase of the invention, the device may be applied or used in any place where a cable, snubbing or hitching post is required, and in such case, it is within the purview of my claims that means may be 50 employed to release the wire or rope from the post by depression of the spring placing the clamping members under compression, whether this means is the operator's hand or a lever for accomplishing this purpose.

Having thus described the invention, what is claimed as new is:

1. A binding post comprising a stem, a plurality of clamping members slidably 55 mounted thereupon, and means for placing said members under compression, said mem-

bers being freely movable along the stem against the compression means and of varying diameters to facilitate manipulation in separating the same to insert a wire or the like.

2. A binding post comprising a base, a stem extending therefrom, a plurality of clamping members arranged in superposed relation and freely movable on said stem, 70 and pressure means interposed between the base and the lowermost clamping member pressing all of said members in a direction away from the base, whereby upon movement of said lowermost clamping member 75 toward the base pressure on the superposed clamping members is relieved to permit insertion of a wire therebetween.

3. A binding post comprising a base formed with an annular seat, a stem connected to said base, a plurality of wire 80 clamping members mounted upon the stem one above the other in contacting relation, and a spring member disposed in the seat, the lowermost of said clamping members 85 being received in the seat of the base aforesaid into coöperation with the spring and constituting an operating member for relieving pressure from the clamping members to permit of insertion of a wire between any 90 of said clamping members.

4. A binding post comprising a base formed with an annular recess, a stem connected to said base, a plurality of wire clamping members mounted upon the stem 95 one above the other in contacting relation, and a spring member disposed in the recess, the lowermost of said clamping members having a gland adapted to be received in said recess into coöperation with the spring 100 and constituting an operating member whereby upon movement of said gland into the recess to relieve pressure from the clamping members.

5. A binding post comprising a base, a 105 stem detachably connected therewith, a cap on said stem, a plurality of clamping members slidably mounted upon the stem in superposed contiguous relation, each member being formed with an annular flange, 110 each succeeding member at its flanged portion being of greater diameter to facilitate separation of the members, and means tending to slide the members along the stem away from the base placing said members 115 under compression.

In testimony whereof I affix my signature in presence of two witnesses.

FREDERICK HENRY DAY.
